UNITED STATES PATENT OFFICE.

GEORGE W. HULSHIZER, OF STEWARTSVILLE, NEW JERSEY, ASSIGNOR TO INGERSOLL-RAND COMPANY, OF JERSEY CITY, NEW JERSEY, A CORPORATION OF NEW JERSEY.

VALVE FOR ROCK DRILLS.

Application filed December 17, 1925. Serial No. 76,016.

This invention relates to rock drills, but more particularly to a distributing valve of the spool type for fluid actuated rock drills.

The objects of this invention are to improve generally valves of this type and to obtain a quick and positive valve action by relieving compression from the ends of the cylinder during a portion of the stroke of the piston and by constantly exposing the ends of the valve to live pressure fluid.

Other objects will be in part obvious and in part pointed out hereinafter.

The invention consists of the combinations of elements, features of construction and arrangement of parts having the general mode of operation substantially as herein-after described and more particularly pointed out in the appended claims and illustrated in the accompanying drawings, in which—

20 Figure 1 is a view in elevation partly in section of a portion of a rock drill showing the valve in position for admitting pressure fluid to the rearward end of the cylinder for impelling the piston forwardly, and

25 Figure 2 is a view similar to Figure 1 illustrating the position of the valve for admitting pressure fluid to the front end of the cylinder to return the piston.

Referring more particularly to the drawings, the invention is shown embodied in a rock drill having a cylinder A which in this instance is provided with a free exhaust port B. Within the cylinder A is a reciprocatory hammer piston C having a forward extension or nose D which cooperates slidably with a front cylinder washer E seated in the front end of the cylinder A to form a closure therefor. The rearward end of the cylinder A is in this instance sealed 40 by a closure F.

The closure F is shown solid and the nose D of the piston C is shown as a plain extension for the sake of simplicity of illustration.

In the present instance a valve chest G having a chamber H is arranged longitudinally of the cylinder A and has an inlet connection J for the admission of pressure fluid to the chamber H from a source of pressure fluid supply. The valve chest G may be either formed integrally with the cylinder A or may be formed separately as indicated in the drawings and secured in position in any suitable manner as for instance by bolts or screws (not shown).

The chamber H is in this instance of uniform diameter throughout its length and is open at its ends to receive sealing plugs K and L. The plugs K and L are provided with central bores O to receive a bolt P provided with a suitable nut Q whereby the plugs K and L may be held securely in position.

Communication between the front and rear ends of the cylinder A and the chamber H is afforded by inlet passages R and S 65 respectively.

In accordance with the present invention annular ports T and U are formed near the front and rear ends respectively of the chamber H, said ports are in constant communication with the inlet connection J through passages V. The passages V may be of any suitable form. In the present instance the passages are of smaller area at the point of communication with the inlet connection J and are flared toward their outer ends, at which point they open to a height approximately equal to the diameter of the ports T and U. Leading from the ports T and U to the front and rear ends of the chamber H are reduced passages W and X through which live pressure fluid may constantly flow to the ends of the chamber H.

Means are provided for permitting the escape of a portion of the atmospheric air entrapped in the cylinder ends by the hammer piston C. To this end, compression relief passages Y and Z are formed to lead from the front and rear ends of the cylinder A to the chamber H. The passages Y and Z are crossed, that is, the passage Z leading from the rearward end of the cylinder A 90 communicates with the chamber H forwardly of the vertical center of the chamber H. In like manner, the passage Y communicating with the front end of the cylinder communicates with a point in the chamber H rearwardly of the vertical center of said chamber.

Within the chamber H is a pressure fluid distributing valve b having a longitudinal bore c which cooperates slidably with the bolt P. The valve b is of the spool type and has a central head d for alternately covering and uncovering the passages Y and Z and end heads e and f. The end heads e and f which control the admission of pressure fluid from the ports T and U to the front and

rear ends of the cylinder respectively are provided with actuating faces *g* and *h* respectively against which pressure fluid may constantly act to assist in throwing the valve 5 in a manner to be hereinafter described. The travel of the valve *b* is in this instance limited by the stops *K* and *L* against which the actuating faces *g* and *h* of the valve may strike.

- 10 Leading from the chamber *H* from a point intermediate the inlet connection *J* and the port *T* is a passage *j* for exhausting entrapped atmospheric air admitted into the chamber *H* through the passage *Z* from the 15 rearward end of the cylinder. A similar exhaust passage *h* is formed between the inlet connection *J* and the port *U* for relieving compression in the front end of the cylinder *A*.
- 20 In the operation of the drill, with the valve *b* in the position indicated in Figure 1, the port *U* will be uncovered by the head *f* of the valve. When the valve is in this position pressure fluid will flow through the 25 passage *V* and the port *U* into the rearward end of the chamber *H* and through the inlet passage *S* to the rearward end of the cylinder *A* and impel the piston forwardly. After the piston *C* covers the free exhaust 30 port *B*, a portion of the atmospheric air entrapped in the forward end of the cylinder will be exhausted through the passage *Y* into the chamber *H* between the valve heads *f* and *d*, from whence it will pass 35 through the passage *h* to the atmosphere. As the piston *C* continues on its forward stroke, the said piston will cover the passage *Y* and during the remainder of its stroke, the remaining portion of atmospheric air 40 in the front end of the cylinder will be compressed and passing through the passage *R* will act against the actuating face *g* and tend to throw the valve *b* rearwardly to the position shown in Figure 2. At about the 45 time that the piston *C* covers the passage *Y*, the piston will overrun the free exhaust port *B* and permit the exhaust of pressure fluid from the rearward end of the cylinder to the atmosphere. This will cause a considerable drop in pressure rearwardly of the 50 valve, and the combined pressures of the compressed air and the live pressure fluid passing through the passage *W* to the front end of the chamber *H* will then exceed the 55 value of the pressure acting against the actuating face *h* and will throw the valve rearwardly to the position illustrated in Figure 2. In this position of the valve the passage *Z* will be uncovered by the central head *d* and thus establish communication 60 between the rearward end of the cylinder and the atmosphere.

In the position of the valve as illustrated in Figure 2, the port *T* will be uncovered by 65 the head *e* and pressure fluid will flow to

the front end of the cylinder *A* for returning the piston. After the piston *C* has travelled a sufficient distance to cover the exhaust port *B*, a portion of the entrapped atmospheric air in the rearward end of the 70 cylinder will pass through the passage *Z* into the chamber *H*, from whence it may pass to the atmosphere through the passage *j*. As the piston continues on its rearward travel, the passage *Z* will be covered. For the remainder of the stroke of the piston the air in the rearward end of the cylinder will be compressed and will act against the actuating face *h* of the valve. After the free 75 exhaust port *B* is again uncovered by the piston *C*, the pressure fluid in the front end of the cylinder *A* will be exhausted to the atmosphere. The pressure fluid acting against the actuating face *g* will then drop to a lower value than the combined pressures 80 of the live pressure fluid from the passage *X* and the compressed atmospheric air which acts against the actuating face *h* and the valve will again be thrown to the position 85 illustrated in Figure 1, thus completing the 90 cycle of operations.

By means of this invention the compressed atmospheric air in the ends of the cylinder may be so controlled as to prevent any retarding effect upon the piston and a quick 95 and positive valve action may be thus obtained.

I claim:

1. In a rock drill, the combination of a cylinder having a free exhaust port, a reciprocating hammer piston in the cylinder controlling said exhaust port, a valve chest having a chamber, said valve chest having inlet passages leading from the ends of said chamber to the ends of the cylinder, crossed passages leading from the ends of the cylinder to points on opposite sides of the center of the chamber for exhausting a portion of entrapped air from the cylinder, the remaining entrapped air passing to that end of the chamber corresponding to the end of the cylinder to which the piston is moving, and a valve having end heads for controlling the admission of pressure fluid through the inlet passages and having a central head alternately covering and uncovering the crossed passages, said outer heads being constantly exposed to live pressure fluid to augment the entrapped air for actuating the valve.

2. In a rock drill, the combination of a cylinder having a free exhaust port, a reciprocating hammer piston in the cylinder controlling said exhaust port, a valve chest having a chamber, admission ports in said chamber in constant communication with a source of pressure fluid supply, inlet passages leading from the ends of the chamber to the ends of the cylinder, crossed passages leading from the ends of the cylinder

to points on opposite sides and adjacent to the center of the chamber for exhausting a portion of entrapped air compressed by the piston, a reciprocating valve in the chamber, said valve having a central head for alternately covering and uncovering the crossed passages, and end heads for controlling the admission ports, and passages leading from

the admission ports to the ends of the chamber constantly admitting live pressure fluid ¹⁰ to both ends of the valve for actuating the valve.

In testimony whereof I have signed this specification.

GEORGE W. HULSHIZER.
